UNITED STATES PATENT OFFICE.

GEORGE H. TOMLINSON, OF CHICAGO, ILLINOIS, ASSIGNOR TO STANDARD ALCOHOL COMPANY, OF NEW YORK, N. Y., A CORPORATION OF MAINE.

PROCESS OF PRODUCING FERMENTABLE SUGARS FROM LIGNOCELLULOSE.

1,032,440.

Specification of Letters Patent. Patented July 16, 1912.

Application filed March 10, 1910. Serial No. 548,443.

To all whom it may concern:

Be it known that I, GEORGE H. TOMLINSON, a subject of the King of England, residing at Chicago, in the county of Cook 5 and State of Illinois, have invented a certain new and useful Improvement in Processes of Producing Fermentable Sugars from Lignocellulose, of which the following is a specification.

10 My invention relates to a process of producing from ligno-cellulose fermentable sugars adapted to be converted into alcohol.

In the accompanying drawing, I have illustrated diagrammatically one form of 15 apparatus whereby my process can be carried out. This apparatus may be described as follows:—A, A, are hoppers adapted to contain ligno-cellulose such as sawdust, and provided with suitable devices not shown 20 for controlling the supply and flow of the same therewith and therefrom. B, B are digesters, each provided with an exterior part C preferably metal, with an interior lining C¹ preferably of acid-resisting brick.

25 Each digester is provided with a blow-off pipe and valve C², a man-hole C³, a removably secured man-hole cover C⁴ and a pressure gage C⁵ which may be attached to the man-hole cover. Each digester is also preferably provided with a worm-wheel D and a driving worm D¹ whereby it may be rotated on its projecting hubs D², D³, mounted in suitable bearings on the standards D⁴, D⁵. Stuffing boxes D⁶, D⁷ are provided at the 30 ends of the hubs for the usual purposes. E is an acid tank adapted to contain, for example, sulfuric acid in its concentrated commercial form. E¹ is a pipe leading thence and controlled by the valve E². This pipe

35 opens into the reservoir F into which leads the water pipe F¹ controlled by the valve F², and from this reservoir leads a pipe F³ controlled by the valve F⁴ to the pressure chamber F⁵. G is a steam supply pipe controlled 40 by the valve G¹ and from it leads the pipe G² controlled by the valve G³ to the pressure chamber F⁶. The steam pipe is connected by the elbow G⁴ to a perforated pipe G⁵ which passes into or through the digester.

45 From the pressure chamber F⁵ leads the pipe J controlled by the valve J¹ to the elbow G⁴, through which it passes and terminates in the nozzle J² preferably placed in the contracted passage J³ in the pipe G⁵.

50 I have shown my apparatus as applied to

two digesters. In this case, a similar set of parts will be applied to the right hand digester as those which have been just described in connection with the left hand digester. One of the objects in using two digesters is to permit the discharge of steam or acid or both from one digester into the other when the first mentioned digester is about to be freed of its load while the second is ready to have steam and acid applied to it. In order to effect such transmission, I employ the system of pipes, valves and couplings illustrated in the drawing.

K is a valve whence leads the pipe K¹ to the T K² whence leads the pipe K³ to the valve K⁴. From the T leads a pipe K⁵ to the valve K⁶ whence leads the pipe K⁷ to the T K⁸ from the opposite ends of which lead pipes K⁹, K¹⁰, to valves K¹¹, K¹², whence lead pipes K¹³, K¹⁴, to couplings K¹⁵, K¹⁶, 60 which are adapted each to coöperate with the coupling K¹⁷ on the blow-off C² when the digester is rotated to bring the parts into the proper position. By a proper manipulation of the valves, it will be seen, that 65 the parts can be so connected that either digester instead of being blown off into the open air can be blown off into the perforated pipe of the other digester. When this is done one of the digesters is rotated until 70 the coupling K¹⁷ can be brought in contact with the coupling K¹⁵. The valve C² is then opened, the steam passing through the pipe K¹³ to the valve K¹⁰ which is also open, 75 through pipe K⁹, T K⁸, pipe K⁷, the open valve K⁶, valve K⁴ and into the pipe G⁵ in the other digester. 80

85 It will be seen that any one of many forms of apparatus could be used to work my process, and that any kind of acid suitable for the purpose may be employed in any state. A stationary digester can be used. Any number of inleading pipes for carrying the steam and acid into the digester may be employed, and they may be 90 associated in any desired manner.

95 In carrying out my process I take any form of ligno-cellulose as, for example, sawdust, and place it in a digester, and then by the use of any desired apparatus, force 100 into the digester steam in such quantity as to raise the temperature of the entire mass up to what is called the critical point or the point where, in presence of acids, particularly strongly hydrolyzing acids, the 105 110

decomposition products which hinder fermentation begin to appear in considerable and objectionable quantities. This is from about 275° to about 325° Fahrenheit. The 5 steam is preferably introduced until the temperature in the digester has been raised to about 212° and thereupon an acid-fluid is introduced into the current of steam and carried by and with the steam into the digester. The acid-fluid is disintegrated by the steam current so that the acid particles are forced into the mass of material in the digester along with, by and at the same time as the steam. The temperature should be 10 raised as rapidly as possible to about 212° Fahrenheit by the introduction of steam alone, and when the acid-fluid is admitted into the steam current, the streams should be so regulated as to give the steam a proper 15 opportunity to disintegrate the acid and under such conditions that the entire predetermined charge of acid is discharged into the digester before the temperature rises above the maximum point or say 325° 20 Fahrenheit. When the entire charge of acid has been inserted the admission of fluid is cut off and the temperature retained at a point, say between 260° and 330° Fahrenheit, for from fifteen to sixty minutes, de- 25 pending upon the nature of the wood, the amount of acid used and other such conditions as may arise from a practical application of the process. The acid may, of course, be forced into the digester with the 30 first admission of steam, but I prefer, for I believe I get better results thereby, to allow the temperature to rise as above stated to 212° Fahrenheit first. This gives a uniform distribution of the acid spray through 35 the stream of steam and, therefore, through the material, and results in less condensation at the immediate neighborhood of the points of entry. By this means also the acid is not brought into contact with the 40 wood until the temperature of re-action is nearly reached and thus I prevent, at least to a degree, the formation of reversion products. The preferred process, therefore, is that wherein a stream of steam is forced 45 into the ligno-cellulose in the digester to heat it to approximately 212° Fahrenheit, and a stream of acid-fluid is then supplied to the stream of steam so as to be disintegrated thereby and carried therewith into 50 the digester, the discharge into the digester being made at numerous points so that the commingled steam and disintegrated acid-fluid are disseminated through the ligno-cellulose, the acid particles, so to speak, be- 55 ing brought into intimate relation with the particles of ligno-cellulose at the time when the latter are heated to a point where conditions are substantially ready for the re-action. 60

65 Any suitable acid for the purpose of

treating the ligno-cellulose can be employed and in any state, though my process is particularly applicable to the employment of acid solutions such as sulfuric acids for the purpose of producing fermentable sugars 70 from ligno-cellulose. All other acids capable of producing the same result can be utilized in my process, the modification thereof being made in such way as to adapt the process to the condition, nature, strength 75 and other peculiarities of the acid desired to be employed. The process is particularly applicable for such hydrolyzing acids as are difficult of volatilization. When the process has been continued long enough, the 80 gases are blown off in any desired manner and the contents of the digester removed, whereupon the fermentable sugar can be secured in the usual manner. The blowing off of the gases involves a rapid reduction of 85 the internal temperature, which falls with the reduction of pressure to or below the atmospheric boiling point of the liquid.

I claim:—

1. The process of producing fermentable 90 sugars from ligno-cellulose which consists in placing a quantity of ligno-cellulose in a closed vessel, quickly raising its temperature by the introduction of steam, introducing a suitable quantity of an acid-fluid into the 95 stream of steam whereby it is disintegrated and disseminated through the ligno-cellulose, maintaining the temperature for from fifteen to sixty minutes at approximately the critical point and then reducing the 100 temperature.

2. The process of producing fermentable 105 sugars from ligno-cellulose which consists in placing a quantity of ligno-cellulose in a closed vessel, quickly raising the temperature to about 212° Fahrenheit by the introduction of steam, introducing a suitable quantity of an acid-fluid into the stream of steam whereby it is disintegrated and disseminated through the ligno-cellulose, continuing the process until the temperature is raised to from 260° to 330° Fahrenheit and maintaining the temperature at such point for from fifteen to sixty minutes and then reducing the temperature. 110

3. The process of producing fermentable 115 sugars from ligno-cellulose which consists in placing a quantity of ligno-cellulose in a closed vessel and discharging a stream of combined steam and acid-fluid into the 120 ligno-cellulose until it is heated to the proper point, then maintaining such temperature by steam thus directly introduced for from fifteen to sixty minutes, and then reducing the temperature. 125

4. The process of producing fermentable 130 sugars from ligno-cellulose which consists in placing a quantity of ligno-cellulose in a closed vessel and discharging a stream of combined steam and acid-fluid into the

ligno-cellulose until it is heated to from 260° to 330° Fahrenheit, then maintaining such temperature for from fifteen to sixty minutes by steam thus directly introduced and 5 then reducing the temperature.

5. The process of producing fermentable sugars from ligno-cellulose which consists in placing a quantity of ligno-cellulose in a closed vessel and discharging thereinto 10 steam and disintegrated acid-fluid through a series of discharge openings so as to bring the acid particles into intimate relation with the ligno-cellulose particles, and continuing the operation until the temperature 15 has reached the proper point, maintaining such temperature for from fifteen to sixty minutes by steam thus directly introduced and then blowing off.

6. The process of producing fermentable sugars from ligno-cellulose which consists 20 in placing a quantity of ligno-cellulose in a closed vessel, heating such ligno-cellulose, forcing a stream of steam and disintegrated acid-fluid into such heated ligno-cellulose

until the proper temperature for the desired 25 re-action is produced, and then maintaining such temperature until the re-action is completed and then quickly reducing the temperature.

7. The process of producing fermentable 30 sugars from ligno-cellulose, which consists in preliminarily heating the mass by direct contact with steam, and then disseminating a hydrolyzing agent through the mass and continuing the heating thereof to effect the 35 conversion.

8. The process of producing fermentable sugars from ligno-cellulose, which consists in preliminarily heating the mass by direct contact with steam, and then conveying a 40 hydrolyzing agent to the mass and disseminating it therethrough by a current of steam, and continuing the heating of the mass to effect the conversion.
